ADJUSTABLE INJECTOR RAZOR

Burnie J. Craig, 1042 La Presa Drive, Pasadena, Calif.
Filed May 14, 1964, Ser. No. 367,296

1 Claim. (Cl. 30—62)

This invention relates to safety razors and particularly to safety razors of the injector types in which new blades are supplied from a blade magazine.

The general object of the invention is to provide an injector razor which is simple in construction and in operation.

A more specific object of the invention is to provide a novel injector type razor wherein a blade seat is integrally mounted on one side of a handle and a clamping member is integrally mounted on the same side of the handle to move towards the blade seat to hold a blade on the seat.

An additional object of the invention is to provide a novel, adjustable, injector razor including a blade seat integrally mounted on a handle.

An additional object of the invention is to provide novel means for adjusting a guard member on an injector razor.

A further object of the invention is to provide an adjustable safety razor wherein a blade seat and a clamping member for holding a blade upon the seat are mounted upon a handle member with the clamping member integrally connected with the rear of the handle and wherein the guard member is integrally connected with the front of the handle and wherein the guard member and the clamping member may each move in opposite directions independent of the other in blade changing and in adjustment.

A more specific object of the invention is to provide a novel adjustable injector type razor wherein a blade seat is integral with a handle and a guard member is mounted on the handle and wherein the guard member is made of a material so that it may move to a limited extent toward and away from the blade seat and is biased to hold a blade securely upon the blade seat while permitting, when desired, the adjustment of the blade exposure and the removal of a blade and substitution of a new blade.

Other objects and advantages of the invention will be apparent from the following description taken in connection with the accompanying drawings, wherein:

FIG. 1 is a front view of the razor;

FIG. 2 is a side elevation of the razor;

FIG. 3 is an enlarged fragmentary central section with parts in elevation taken on line 3—3, FIG. 1;

FIG. 4 is a section taken on line 4—4, FIG. 1;

FIG. 5 is a section taken on line 5—5, FIG. 1;

FIG. 6 is a fragmentary front view showing the body or handle;

FIG. 7 is a side elevation of the body;

FIG. 8 is a front view showing the blade seat;

FIG. 9 is a side elevation showing the blade seat;

FIG. 10 is a rear view showing the blade seat;

FIG. 11 is a front view of the adjusting dial;

FIG. 12 is a rear view of the adjusting dial;

FIG. 13 is a fragmentary front view showing the clamping member;

FIG. 14 is an enlarged fragmentary section taken on line 14—14, FIG. 1;

FIG. 15 is a fragmentary front view showing a detail of the adjustable guard member;

FIG. 16 is a perspective view showing a stop pin;

FIG. 17 is a diagram showing the development of the cam and its followers; and

FIG. 18 is an elevational view showing a blade magazine.

Referring to the drawing by reference characters the

2

invention is shown as embodied in a razor of the injector type which is indicated generally as at 10. The razor, as shown, includes an elongated body or handle 11. A blade seat 12 is mounted upon the upper end of the body. The blade seat 12 includes a forwardly extending blade receiving portion having lugs or blade stops 13 thereon for engagement with the front end edges of a blade 14 disposed on the seat 12.

The seat 12 includes a depending portion 15 which is disposed on the rear of the body 11 in a cut away portion 16. The blade seat 12 and the depending portion 15 are integrally mounted on the body by means such as welding or gluing at 17. The depending portion 15 includes a groove 18 in its rear face to receive a cam finger 19 on a blade magazine 20.

In order to hold a blade upon the blade seat 12 I provide a clamping member indicated generally at 25. As shown, the clamping member includes a forwardly projecting blade clamping portion 26 and a depending portion 27 which is integral with the portion 26 and which extends along the rear face of the body 11. The lower end of the clamping member is shown as secured to the body by a screw 28 which passes through the body and engages an internally threaded collar 29 which is integral with the depending portion 27.

The depending portion 27 is also secured to the body by a threaded collar 30 on the depending portion which engages a screw 31 which passes through the body and the seat depending portion. The depending portion 27 is shown as provided with forwardly projecting short flanges 32 which are arranged at each side of and in the center of the depending portion 27 and which fit in slots 32' in the blade seat depending portion 15. The flanges 32 may serve to guide the clamping member depending portion as it moves back and forth and the flange at the right in FIG. 13 receives and guides the cam finger 19 on the blade magazine 20.

A flange 32' disposed opposite to the flanges 32 serves to guide the upper edge of the cam finger.

The clamping member depending portion is made of a material such as metal, plastic, et cetera, so that it can move backwardly and forwardly to a limited extent and it is biased to move forwardly to urge the blade clamping portion 26 forwardly and downwardly upon the blade and to force the blade 14 against the lugs 13. A stop pin 34a centrally disposed on the clamping member contacts the rear of the blade in this blade holding action.

To change a blade the operator inserts the finger 19 of the blade magazine into the groove 18 with the lower end of the finger engaging one of the flanges 32. As the finger advances, the cam 19a thereon engages the wall of the groove 18 and is pushed away from the rear of the blade seat. The rear face of the cam finger being in engagement with the front face of the clamping member depending portion 27 will move this depending portion 27 rearwardly against its bias to thereby release the pressure of the portion 26 and the stop pin 34a on the blade and thus allow a new blade from the magazine 20 to be pushed into place and at the same time push out the old blade. When the blade exchange is completed the blade magazine with its finger will be withdrawn.

The screw 31 as well as the fastening means such as welding or gluing as at 17 serves to hold the blade seat depending portion 15 integral with the handle 11.

The blade seat 12 is recessed as at 33 between the blade seat ends 33' on which the lugs 13 are arranged. The recess 33 receives a guard member indicated generally at 34, as will be later described. The upper end 35 of the body 11 is disposed in line with the recess 33 and helps to support the central portion of the blade seat 12.

The guard member 34 includes a transversely extending rigid guard portion 36 which is disposed just below

the cutting edge 37 of the blade 14 and extends forwardly and rearwardly of the cutting edge. The guard portion 36 is rounded as at 38 and may be longitudinally grooved as at 39.

The guard member has ends 40 (FIG. 15) thereon which are connected to a depending portion 41. The guard member ends 40 and the guard portion 36 are cut away as at 42 so that the ends 40 may be positioned under the blade seat ends 33' of the seat and under the lugs 13 on the ends 33'.

The guard member has a slot 44 therethrough to allow soap and cut whiskers to pass away from the blade cutting edge.

The depending guard portion 41 may be secured as by gluing or welding as at 45 to the body 11. The depending portion 41 may also be secured as by a screw 46 to the body 11.

By moving the guard member 34 the guard portion 36 thereon may move backwards and forwards under the blade seat so that the amount of blade exposure may be varied and consequently the closeness of the shave may be adjusted.

The body 11, the blade seat 12, the clamping member 25 and the guard member 34 may be made of suitable material, such as metal or plastic. If plastic is used it may be of the thermoplastic or of thermo-set type and may be such a polycarbonate, polypropylene, polyethylene, Plexiglas, Celcon, nylon, styrene, polyester, epoxy or similar material which has suitable characteristics. If metal is used it may be steel, stainless steel, brass or other metal.

The body, blade seat, clamping member and guard member may be of the same material or of different materials. It is preferable that one or more of these be made of a material so that the members may move relatively to each other forward or backward to a limited extent and may be biased to move in one direction. In the embodiment described herein the blade seat is preferably integrally connected to the body and the clamping member moves backwardly and forwardly in the blade clamping operation.

The blade clamping member 25 is biased to move forwardly so that the portion 26 forces a blade downwardly upon the blade seat and the stop member 34a engages the rear end of a blade on the blade seat and pushes the front edge of the blade against the lugs 13.

In order to move the guard member 34 so that the guard portion 36 thereof may be shifted relative to the cutting edge of a blade 14 on the blade seat 12 I provide an actuating member indicated generally at 50 which as shown includes a dial 51. The dial 51 is arranged in a recess 52 in the front face 53 of the body 11. The dial 51 has a shaft 54 which extends forwardly from one side thereof and is fitted in a hole 55 in the depending guard portion 41. A hub 56 on the dial engages the rear face of the depending guard portion 41.

On the other side of the dial, the shaft 54 has a cam rod 57 extending therethrough. The cam rod is fixed in position as by welding or the dial assembly may be a plastic or die casting. The shaft 54 beyond the cam rod 57 passes through a hole 58 in a cam member 59. The cam member 59 is mounted in a recess 60 in the body 11 or may be cast integral with the body. When the shaft 54 is rotated it causes the cam rod 57 to move across the cam face 61 on the cam member 59 so that when the dial 51 is turned in one direction it forces the depending guard portion 41 forwardly. When the dial 51 is turned in a reverse direction the bias of the depending guard portion 41 cause this portion to move rearwardly to thus cause the guard portion 36 to move rearwardly under the cutting edge.

The depending guard portion 41 has an arcuate slot 63 therein. The dial 51 has a wing 64 thereon which moves in the slot 63 as the blade exposure adjustment is made. The ends of the slot 63 limit rotation of the wing 64 and the dial in each direction.

The construction is such that when the dial 51 is rotated by movement of the wing 64 the cam rod 57 which engages the cam faces 61 on the depending guard portion 42 will be rotated. The depending portion 41 of the guard member is biased to move rearwardly so that the cam faces 61 are normally urged toward the cam member 59. When the cam rod 57 is rotated in one direction it will, due to its engagement with the cam faces 61, cause the cam member 59 to move forwardly and consequently will cause the depending guard portion 41 to move forwardly to thus shift the guard portion 36 and increase the blade exposure. When the wing is rotated in anti-clockwise direction it causes the guard portion to move rearwardly to decrease the blade exposure.

If it is desired to hold the dial 51 in a set position and therefore maintain the desired blade exposure the upper half of the dial periphery may be provided with tooth-like serrations 66. A spring member 67 having an end portion 68 embedded in the body 11 has a free end disposed in the upper part of the recess 52.

The spring is disposed above the axis of the dial 51. The spring is biased so that the free end thereof is urged towards the axis of the dial and into engagement with one of the peripheral teeth 66 on the dial.

The teeth 66 have inclined faces and when the dial is rotated one of the inclined faces will force the spring away from the dial axis until the peak of the tooth is reached, whereupon the spring will drop into the next tooth and this action will continue until the desired adjustment is secured and the dial turning has ceased, whereupon the spring portion 67 will enter the tooth aligned therewith and will hold the dial and the guard member in the desired adjustment.

Having thus described the invention, I claim:

35 A razor including an elongated body, a blade seat upon the upper end of said body, said blade seat being immovable with respect to the body, said blade seat including a blade receiving portion having blade stops thereon for engagement with the front end edges of a blade on the blade receiving portion, a separately formed clamping member including a forwardly projecting blade engaging portion adapted to hold a blade upon the blade seat, said clamping member also including a depending portion disposed upon the rear of the body and integrally united 40 to the body at a location below the blade seat, said clamping member depending portion being made of a material having resilient characteristics so that it may move backwardly and forwardly to a limited extent, stop means associated with the blade clamping member and adapted 45 when the clamping member is in clamping position to urge a blade on the blade receiving portion into engagement with the blade stops, said clamping member depending portion being biased due to the resiliency of the material from which it is made to move forwardly to urge 50 the blade engaging portion forwardly to clamp a blade upon the blade seat, there being a slot in advance of said clamping member depending portion for the reception of a cam finger on a blade magazine, the cam finger being adapted to move the clamping member and its blade engaging portion in a direction away from the blade seat, and a guard member for a blade upon the blade seat, said guard member being free of attachment to the blade seat, said guard member including a guard portion disposed below the cutting edge of a blade on the blade seat, said guard member including a depending portion 55 which supports it, said guard member depending portion being secured to the front of the body at a location below and remote from the blade seat, the guard depending portion being made of a material having resilient characteristics so that it may move backwardly and forwardly to a limited extent to thereby move the guard member and the guard portion backwardly and forwardly with regard to the blade seat and under the blade seat while the blade seat remains stationary, the guard depending portion being biased due to the resiliency of the material from which 60 65 70 75

it is made to move in one direction, and manual means operable to move the guard depending portion in a reverse direction and against the bias of said guard depending portion to thereby shift the guard portion and change the blade exposure.
